UNITED STATES PATENT OFFICE

WASHINGTON T. CAPPS, OF BALTIMORE, MARYLAND

LOCOMOTIVE STOKER

Application filed August 9, 1929. Serial No. 384,557.

One of the objects of the invention is to combine the fuel distributor mechanism into two parts thereby reducing the number of parts to be carried by a railroad in its storehouse.

Another object of my invention is to so position the forward bottom portion of the fuel distributor below the bottom surface of the tube that less steam pressure is required to distribute the fuel.

Another object of my invention is to taper the tube at the forward end to aid materially in reducing the jet pressure used to blow the coal from the distributor over the grate area, and eliminate the clogs frequently occurring in the distributor tube and also to allow the large lumps of coal free passage in to the channels on each side in the bottom portion of the distributor.

Another object of my invention is to provide means to hold the distributor tube in proper position so that it will automatically line up the bottom surface of the tube as it is drawn up tight in the discharge member and prevent it from being tilted at an angle toward the side sheet of the firebox or fire door, thus eliminating uneven distribution of fuel.

Another object of my invention is to so secure the forward end of the distributor top and bottom to prevent enginemen, hostlers, fire-up men, and others from disengaging these parts either wilfully, or accidentally without entering the firebox.

A further object is to provide means for raising and lowering, or properly focusing the distributor mechanism, also preventing side movement at forward end.

In the drawings:

Figure 1 is a vertical longitudinal section of my improved stoker distributor with associated parts in dotted lines.

Figure 2 is a top plan view of my improved stoker distributor detached.

Figure 3 is a front elevation of my improved stoker distributor.

Figure 4 is a vertical section on the line 4-4, Figure 1, the cotter pin being omitted.

Figure 5 is a sectional view on the line

5-5, Figure 2, showing the travel of the fuel.

Figure 6 is a detail sectional view on the line 6-6, Figure 5.

Figure 7 is a detail sectional view of the forward part of Figure 5.

Figure 8 is a sectional view on the line 8-8, Figure 7.

Figure 9 is a detail sectional view on the line 9-9, Figure 7.

The reference numeral 5 designates the back sheets of a fire box of a locomotive in which is mounted a fire tube 6 which constitutes an aperture through which my improved stoker distributor projects. The discharge member 7 of the stoker is provided with a boss 8 having a bolt aperture 9 in which the body shank of the bolt 10 is positioned, said bolt being provided with a nut 11. This bolt as best seen in Figure 2 is provided with a T head 12 which will be hereinafter more fully referred to.

The distributor tube 13 is flared from its rear to its forward end so that this tube has a cross sectional area at its front end materially in excess of that at its rear end, the object of which is to materially prevent the clogging of the tube when the wet coal is encountered or large lumps accidentally wedge in the tube. The rear portion at the bottom of the tube is thickened to prevent the abrasive action of the coal cutting it through.

The tube 13 is provided on its upper surface at its rear end with two spaced vertically disposed lugs 14 between which is a boss 15 constituting an inclined supporting surface between the lugs. The forward ends of the lugs are each provided with a recess 16 into which the T head 12 of the bolt 10 is seated. Spaced from and in front of the forward ends of the lugs 14 is a lug 17 which functions to limit the forward movement of the T head of the bolt 10 but permits sufficient forward movement of the T head of the bolt 10 for the T head to slide out of and free from the recesses 16 when it is desired to disconnect the distributor tube. These lugs 14 being spaced apart and being closely engaged by the T head of the bolt automatically level the distributor tube 13 when

the bolt is drawn tight into the discharge elbow by the nut 11. Therefore the coal cannot be distributed unevenly to the side sheet or to the central part of the fire box as happens when the distributor tube is tilted or revolved, which is possible in some of the constructions used prior to my invention.

The lugs 14 provide a two point suspension for the distributor tube 13 which functioning with the T head of the bolt 10 hold the distributor tube 13 against accidental revolution on its axis. The bolt 10 firmly clamps the tube 13 to the discharge end 7 as clearly shown in Figure 1. It will be noted that only the upper part of the tube 13 comes in contact with the discharge member 7 the lower portions of the discharge member and tube being purposely spaced apart for allowing of vertical adjustment of the tube 13 by means of two bolts 16 herein-after described. The distributor tube 13 is provided on its under face with two lugs 14 having bolt threaded openings into which set screws 16 are adjustably fitted, the head 25 of the bolts 16 resting on the bottom of the firing tube or aperture 6, as shown in Figure 1, which screws respectively afford a third and a fourth point of suspension. By adjusting the screws 16 the weight of the front 30 end of the distributor tube is supported and stress of weight is divided between the bolt 10 and set screws 16. The tube 13 is provided near its forward end with exterior lugs 17' on its sides and a lug 18 on the top, the lug 18 35 being perforated to permit the passage of a cotter pin or equivalent fastening means 19. At the top and bottom on the forward end of the tube 13 I provide spacing lugs 20 to be hereinafter referred to.

40 The distributor top deflector plate 21 and bottom delivery plate 22 are cast or formed integral with the band 23, said band terminating in upstanding lugs 24 on the top 21 having cotter pin openings 25 registering, when 45 assembled, with the opening in lug 18 on the distributor tube 13, (see Figure 4) in which position they are secured to the lug 18 by the cotter pin 19, or other fastening device. The reinforcing web 31 helps to support the plate 21 and join it firmly with the band 23. As will be seen in Figure 4 the lugs 20 on the end of the distributor tube 13 space the band 23 from the end portion 50 of the tube 13 thereby providing a space between these two elements through which air 55 may freely circulate, thereby protecting the forward end of the tube 13 from injury from the high temperatures of the fire box. From the above it will be seen that it is impossible 60 to remove the deflector plate and delivery plate 21 and 22, from tube 13, without first entering the fire box and removing the cotter pin 19. Again, it will be seen that in the event of the plates 21 and 22 becoming damaged from any cause they can be readily re-

moved for repair or replacement by simply removing the cotter pin 19. Owing to the air space between the forward end of the tube 13 and the band 23 it is seldom, if ever, that the forward end of the tube 13 is damaged. It will be seen that the entire distributor apparatus consists of but two parts, namely, the feed tube 13 and the distributor head comprising the integral band 23 top and bottom plates 21 and 22, which is an important factor in that it reduces the number of parts to be carried in stock in the storehouse of the railroad. The lugs 17' on the tube 13 limit the backward movement of the head 23 on the forward end of the tube 13.

The feed tube 13 has three zones on its lower inner face, viz: A central zone 24' which is substantially parallel with the center line of the tube and arranged to feed fuel to the forward part of the fire box; and side zones 25' pitched downwardly and outwardly from the center zone and toward the sides of the tube 13 and designed to feed the fuel to the diverging channels 26 in the distributor plate 22. The diverging channels 26 dis-

tribute the fuel to the rear end and sides of the fire box, while the central zone 27 of the bottom plate 22 feeds the fuel to the forward portion of the fire box. In this connection it will be noted that there is no obstruction in the path of the flow of fuel through the tube 13 or over the bottom delivery plate 22, the bottom distributor as a whole being set in a lower plane than the forward end of the tube 13, the firing surface of the delivery plate consisting of an unobstructed central portion 27 and diverging channels 26. Then it will be noted that the sunken portion 25' of the tube 13 feeds fuel to the divergent channels 26, and that the flat portion 24' in conjunction with the portion 27 of the plate 22 forms a smooth sliding surface for the fuel that is fed to the forward portions of the fire box.

It will be noted that this sunken portion starts at the rear of the tube 13, and gradually deepens as it approaches the plate 22, and thus feeds the coal into the divergent channels 26 where it slides along the curved portion, and is thus directed in a direction perpendicular to that in which it entered.

The rear portion of the floor of the tube 13 is increased in thickness and chilled, as at 30, to a degree of hardness necessary to prevent abrasion by the coal that is being accelerated in this vicinity by the action of the steam jet 29.

As will be seen from Figure 5, the coal in each channel and on the central flat portion is interlocked and, therefore, easily progresses in their respective streams and more readily and evenly discharges into the diverging channels of the delivery plate and over the flat central zone of the distributor.

As will be seen the band 23 and the plates 21 and 22 are integrally cast and form a uni-

70

5 tary distributor secured by the cotter pin 19 to the forward end of the tube at the top, and held to the forward end of the tube by its own weight. The lugs 17 are engaged by the band 23 whereby the backward movement of the distributor is limited relative to the forward end of the tube.

What I claim is:

1. In a locomotive stoker, the combination 10 with a fuel feed device, of a distributor tube, a pair of spaced holding members extending upwardly from the upper face of the tube and near the rear end thereof, and a connecting element between the fuel feed device and the tube engaging said holding members and detachably and pivotally connecting the tube and the fuel feed device.

2. In a locomotive stoker, the combination 20 with a fuel feed device, of a distributor tube, a pair of spaced lugs extending upwardly from the upper face of the tube and near the rear end thereof, a suspending member engaged with the fuel feed device and extending between said lugs and engaging the ends 25 thereof, and a transversely extending lug spaced forward from and bridging the space between said first named lugs and holding said fastening member from forward displacement.

3. In a locomotive stoker, the combination 30 with a fuel feed device, of a distributor tube, a pair of spaced lugs extending upwardly from the upper face of the tube near the rear end thereof, said lugs having recesses in the forward end walls thereof, and a suspending member engaging the fuel feed device and lying between said lugs and having a head engaging the recesses thereof.

4. In a locomotive stoker, fuel delivery 40 means comprising a discharging member, provided with a lug having a bolt hole therethrough, a distributor tube designed to extend from the member through the back wall of a locomotive fire box, a pair of spaced lugs 45 extending upwardly from the upper face of the tube and near its rear end, a substantially T headed bolt for holding the tube to the said discharging member, the head of the bolt engaging the forward ends of the said lugs while the shank of the bolt is removably disposed between said spaced lugs and in the bolt opening in the lug on the discharge member, and a nut on said bolt bearing against the lug on the discharge member.

5. In a locomotive stoker, fuel delivery 50 means comprising a discharging member, provided with a lug having a bolt hole therethrough, a distributor tube designed to extend from the member through the back wall 55 of a locomotive fire box, a pair of spaced lugs extending upwardly from the upper face of the tube and near its rear end, a substantially T headed bolt for holding the tube to the said discharging member, the head of the bolt engaging the forward ends of the said

6 lugs while the shank of the bolt lies between said spaced lugs and in the bolt opening in the lug on the discharge member, and a nut on said bolt bearing against the lug on the discharge member, and an upwardly extending lug near but spaced forward from the forward ends of said spaced lugs to limit the forward movement of the head of said bolt.

7. In a stoker, the combination with a distributor tube, of a band detachably secured at the outlet end of said tube, and forwardly projecting distributor means extending from the top and bottom portions only of the band.

8. In a stoker, the combination with a distributor tube, of a distributor extension unit detachably secured at the outlet end of said tube and comprising a band surrounding the outlet end of the said tube, and extensions cast integrally with said band and projecting forward from the outlet end of the tube at the top and bottom portions only of said band.

9. In a stoker, the combination with a distributor tube, of a distributor top and bottom secured to the forward end of said tube, and means spacing the tube circumferentially from said top and bottom.

10. In a locomotive stoker, a back head of a locomotive, a firing tube fastened in said back head, a stoker tube positioned in said firing tube, and means adjustable supporting a portion of the weight of said distributor tube on the firing tube.

11. In a locomotive stoker, a back head of a locomotive, a firing tube fastened in said back head, a stoker tube positioned in said firing tube, and means disposed on opposite sides of the longitudinal center of the tube for supporting a portion of the weight of said stoker tube on the firing tube, said means being adjustable to properly position the forward end of the distributor tube.

12. In a locomotive stoker, the combination with a discharge member, an aperture in the back head of a locomotive fire box, a distributor tube extending through said aperture for delivering fuel into the fire box of the locomotive, means for holding said tube to said member, and means adjustably supporting the tube intermediate its ends in said aperture.

13. In a locomotive stoker, a distributor tube having an upstanding central zone substantially parallel with the center axis of the tube, and two side zones pitching downwardly and outwardly and a distributor bottom secured to the forward end of the said tube and provided with a zone corresponding to the central zone of the tube and side diverging channels open at their rear ends to the side zones of the said tube.

14. In a stoker, a fuel distributing tube,

- and a removable forward distributing member ahead of the said tube, fuel channels in the bottoms of said tube and member, the channels in the tube extending from end to end of said tube and registering with the channels in the said member.
15. In a locomotive stoker, the combination with a distributor tube, of a distributor head comprising top and bottom plates and a band integral with the rear ends of said top and bottom plates secured to the forward end of said distributor tube.
16. In a locomotive stoker, the combination with a distributor tube, a lug at the forward end and on top of said tube, of a distributor top and bottom, a band integral with said top and bottom having lugs at its ends, adapted to be secured to the lug on the tube.
17. In a locomotive stoker, the combination with a distributor tube, a lug at the forward end and on top of said tube, of a distributor top and bottom, a band integral with said top and bottom having lugs at its ends, adapted to be secured to the lug on the tube, and means spacing the band circumferentially from the tube to provide an air space.
18. In a locomotive stoker the combination with a distributor tube, a lug at the forward end and on top of said tube, of a distributor head comprising top and bottom members, a band integral with said top and bottom members and having lugs at its ends pivoted to the lug on the tube, and means to limit the rearward swinging movement of the head on the said tube.
19. In a stoker the combination with a distributor tube, of a distributor head comprising integrally connected top and bottom members pivotally secured at its top to the forward end of said tube and bearing by gravity at its base against the end of the tube, and means limiting the backward movement of said distributor head relative to the forward end of the said tube.
20. In a locomotive stoker a fuel distributor tube having a plurality of forwardly sloping channels extending from end to end thereof, said channels having a gradually increasing depth toward the discharge end of the tube.
21. In a locomotive stoker, a locomotive having a fire box provided with a firing opening, a fuel feed device located outside the fire box, a distributor tube extending from the fuel feed device through the firing opening into the fire box, means detachably suspending the distributor tube at the upper portion of its outer end from the fuel feed device, so as to adapt said tube to have pivotal motion in a vertical plane, and supporting means carried by the tube and engaging a wall of the firing opening for supporting said tube and pivotally adjusting the same on said pivotal connection.
22. In a locomotive stoker, the combination of a locomotive having a fire box provided with a firing opening, a fuel feed device located on the outer side of the fire box, a distributor tube extending from the fuel feed device into the fire box through the firing opening, means pivotally and detachably suspending said tube coincident with its longitudinal center at the upper portion of its outer end from the fuel feed device, and supporting devices arranged on opposite sides of the longitudinal center of the tube and resting against the bottom wall of the firing opening and adjustably supporting said tube on said pivotal connection.
23. In a locomotive stoker, a locomotive having a fire box provided with a firing opening, a fuel feed device arranged on the exterior of the fire box, a distributor tube extending from said fuel feed device into the locomotive through the firing opening, means at the upper rear end of said distributor tube pivotally suspending the same from the fuel feed device, supporting means between the tube and the wall of the firing opening for adjustably supporting the tube in the firing opening, a distributor plate at the inner end of the tube, and means detachably fastening said plate to the tube within the fire box.
24. In a locomotive stoker, a locomotive having a fire box provided with a firing opening, a fuel feed device located outside the fire box, a distributor tube extending from said fuel feed device through the firing opening into the fire box, means detachably suspending said tube at its upper end rear ends from the fuel feed device, means for adjustably supporting the tube intermediate its ends within the firing opening, and a distributor head at the inner end of the tube comprising top and bottom plates and a member uniting the same, said head being pivotally and detachably mounted at its upper portion upon the tube.
25. In a locomotive stoker, a distributor tube having its bottom surface provided with a central longitudinally extending raised portion, and channels at opposite sides thereof, said channels sloping at a gradually increasing depth from the inlet end to the outlet end of the tube.
26. In a locomotive stoker, a distributor tube flaring uniformly between its inlet and outlet ends and having its bottom provided with a central longitudinally extending raised portion and channels at opposite sides thereof, said channels sloping on a gradually increasing pitch from the inlet to the outlet end of the tube.
27. In a locomotive stoker, a distributor tube having its bottom provided with a central longitudinally extending raised portion and channels at opposite sides thereof, said channels sloping so as to gradually increase in depth between the inlet and outlet ends of the tube, and a distributor plate at the inner

end of the tube having a raised central portion located below the plane of the central portion of the tube bottom and provided at opposite sides of said central portion with 5 depressions communicating with the channels of the tube and opening through the opposite sides of the distributor plate.

28. In a locomotive stoker, a distributor tube of flaring form between its inlet and 10 outlet ends and having its bottom provided with a central longitudinally extending raised portion and channels at opposite sides thereof, said channels sloping so as to gradually increase in depth between the inlet and outlet 15 ends of the tube, and a distributor plate at the inner end of the tube having a central raised portion in longitudinal alinement with but located below the level of the central raised portion of the tube and depressions at 20 opposite sides of said raised portion communicating with and deeper than the channels of the tube and opening through the opposite sides of the plate.

29. In a locomotive stoker the combination 25 with a discharge member and a distributor tube, a pair of spaced lugs extending upwardly from the upper side of the tube near the end thereof, and recessed in the forward end walls of said lugs, connecting means 30 between said discharge member and said distributor tube, said connecting means adapted to engage said recesses.

30. In a stoker, the combination with a 35 distributor tube, of a unitary distributor head detachably hinged at the outlet end of said tube and comprising substantially flat integrally cast top and bottom walls.

31. In a locomotive stoker, a firing tube, a discharge member, a distributor tube suspended 40 at its top and near its rear end from the discharge member, and a pair of supporting members intermediate the ends of the distributor tube and engaging the firing tube.

32. In a stoker, the combination with a distributor tube, of a distributor head comprising 45 integrally connected top and bottom members pivotally suspended at its top from the forward end of said tube and gravitally bearing at its base against the end of the 50 tube.

33. In a locomotive stoker, a distributor tube, and a distributor bottom detachably secured to the forward end of said tube, the central portion of the lower wall of the tube 55 and of the top surface of said distributor bottom being raised, the side portions of the lower wall of the tube and of the top surface of the distributor bottom being depressed, the raised portion extending the full length 60 of the tube, and the height of the raised portion with relation to said side portions being greater at the forward end of the tube than at the rear end thereof.

34. In a locomotive stoker, a distributor 65 tube, a distributor bottom detachably secured

to the forward end of said tube, a central portion of the lower wall of the tube and a central portion of the top surface of said distributor bottom being raised, side portions of the lower wall of the tube and of the top 70 surface of the distributor bottom being depressed to form continuous unobstructed fuel guide channels in the tube and distributor bottom, the depth of said channels with relation to said raised portions gradually and 75 progressively increasing toward their forward ends.

In testimony whereof I affix my signature.
WASHINGTON T. CAPPS.

DISCLAIMER

1,875,216.—*Washington T. Cupps*, Baltimore, Md. LOCOMOTIVE STOKER. Patent dated August 30, 1932. Disclaimer filed October 17, 1935, by the assignee, *The Standard Stoker Company, Inc.*

Hereby enters this disclaimer to that part of the claim in said specification which is in the following words, to wit:

“11. In a locomotive stoker, the combination with a discharge member, an aperture in the back head of a locomotive fire box, a distributor tube extending through said aperture for delivering fuel into the fire box of the locomotive, means for holding said tube to said member, and means adjustably supporting the tube intermediate its ends in said aperture.”

[*Official Gazette November 5, 1935.*]
